DIGITAL ELECTRONIC PENDANT WATCH

Francoise Glarner, Geneva, Switzerland, assignor to
Bulova Watch Co., Inc., New York, N.Y.

Filed Aug. 15, 1974, Ser. No. 497,761

Term of patent 14 years

Int. Cl. D10—02

U.S. Cl. D10—30

FIG. 1.

FIG. 2.

FIG. 3.

FIG. 4.

FIG. 1 is a right front perspective view of a digital electronic pendant watch showing my new design;

FIG. 2 is a front elevational view thereof;

FIG. 3 is a right side elevational view thereof, the left side being a mirror image thereof; and

FIG. 4 is a rear elevational view thereof.

I claim:

The ornamental design for a digital electronic pendant watch, substantially as shown and described.
